UNITED STATES PATENT OFFICE.

RUDOLPH L. STADNICK, OF ST. LOUIS, MISSOURI, ASSIGNOR OF ONE-HALF TO THOMAS E. VODICKA, OF ST. LOUIS, MISSOURI.

DESIGN FOR A GAME-BOARD.

57,160.

Specification for Design.

Patented Feb. 22, 1921.

Application filed July 26, 1920. Serial No. 399,200. Term of patent 7 years.

To all whom it may concern:

Be it known that I, RUDOLPH L. STADNICK, a citizen of Czechoslovakia, Europe, residing at St. Louis, in the State of Missouri, have invented a new, original, and ornamental Design for a Game-Board, of which the following is a specification, reference being had to the accompanying drawing, forming part thereof.

The figure is a plan view of a game board, showing my new design.

I claim:

An ornamental design for a game board, as shown.

RUDOLPH L. STADNICK.
